UNITED STATES PATENT OFFICE

ALEXANDER P. BLOOD, OF NEW YORK, N. Y.

INSULATOR

Application filed February 18, 1929. Serial No. 340,782.

This invention relates to sheet mica insulators, such as are commonly employed in connection with electric heating elements.

In many devices, for instance an electric flat iron, the electric conducting and heating element is in the form of a flattened coil encircling an insulation sheet and is held between two other insulation sheets. These sheets or plates have heretofore usually been cut from a sheet of mica of the desired thickness or from an artificial sheet made of mica splittings superposed to give the desired thickness and cemented together by means of shell-lac, silicate of soda or other cementing material. The pure mica sheets are comparatively expensive and in cutting them there is a very considerable waste in the form of trim. The artificial sheets made of splittings and cement are comparatively stiff, and although they may be made by use of the trim from pure mica sheets, the trim from the built up and cemented sheets cannot be again used. Thus a considerable amount of mica is wasted.

The main object of my invention is to provide a mica insulator which is a great deal cheaper than either the pure mica or the sheet of cemented splittings, and which is equally effective as an insulator.

In carrying out my invention all of the trim from the sheets may be used in the making of other sheets, so that there is no waste of mica. Furthermore my improved sheets are made solely of mica splittings which are very inexpensive and do not require any shell-lac or other cement for holding the mica splittings together and in proper relative positions.

In carrying out my invention I use merely mica splittings and water or other readily volatile liquid, and build up the sheet to the desired thickness. The surface tension of the water will hold all of the mica splittings together and in the proper relative positions so long as the water remains between the mica layers. Thus the sheet with the pieces of mica of varying sizes held together solely by the surface tension of the water, may be cut to the desired shape and assembled in the final position in respect to the heating element.

In this final position it is subjected to pres-

sure which drives out most of the water and to gentle heat which drives out the rest so that only the mica splittings remain. Due to the fact that they are now under pressure they will hold their relative positions and serve just as effectively as an insulator as would a sheet of unsplit mica or a sheet in which the mica splittings are cemented together.

By means of my invention I very materially reduce the cost of the insulator, provide effective insulation, and use up all of the mica because the trim from one sheet of mica splittings held together with water, may be dried and the small pieces readily separated and used in building up another sheet.

My invention may be used as an insulator in a wide variety of different kinds of apparatus, it only being essential that the condition of use be such that the insulator is encased or held under sufficient pressure to prevent the shifting about of the small pieces of mica after the water has been dried out.

In the accompanying drawing I have illustrated merely one embodiment of my invention.

In the drawing:

Fig. 1 is a perspective view of a heating element embodying my invention and adapted for use in a flat iron;

Fig. 2 is a transverse section on the line 2—2 of Fig. 1, the parts being shown somewhat diagrammatically and greatly increased as to thickness;

Fig. 3 is a plan view of the device shown in Fig. 1, the outer metal casing being removed and a portion of the upper insulating sheet being broken away to show the heating element;

Fig. 4 is a transverse section on the line 4—4 of Fig. 3, but very much enlarged as to thickness and spacing of the parts; and

Fig. 5 is a plan view of the heating element and the sheet upon which it is wound.

In carrying out my invention I employ mica splittings which may vary in thickness and in size, but all of which are comparatively thin. These are thoroughly wet and distributed on a suitable support so as to build up a sheet of the size and thickness desired.

and of substantially uniform thickness. The fact that the splittings are wet will retard the tendency of the sheets to slide around upon each other, but will not prevent them 5 from being manually moved about to get the desired distribution and uniformity as to thickness. The sheet may then be pressed so as to force out a major portion of the water and to distribute the remaining water in very 10 thin films between the contacting surfaces of superposed splittings. These very thin films of water will exert such surface tension as will hold all of the pieces together and will prevent any shifting. The sheet may then 15 be handled the same as a sheet of pure mica or a cemented sheet, although, of course, somewhat greater care should be exercised to prevent undue pressure or bending strains. The sheet in this condition may be cut in a 20 punch press to the desired shape, and if desired, it may be slotted or perforated in accordance with the use to which it is to be put.

A sheet 11 made up of splittings merely held together by films of water may be cut 25 of a size and shape for use in a flat iron and has a central slot 12, rivet holes 13, and slots 14 for the leads to the heating element. Two such sheets may be employed, one beneath the heating element and the other above. 30

The heating element itself may be wound upon a sheet made in the same way as the sheet 11 above referred to.

As shown there are two comparatively narrow sheets 15 which are provided with 35 notches along opposite sides and are placed upon opposite sides of the slot 12. An electric resistance element 16 is wound around two of these sheets 15 in series and connected to leads 17 which may be extended through 40 the slots 14 in one of the sheets 11. The successive turns of the resistance element are held in proper spaced relationship by winding the element in the notches on the edges of the sheets 15. The pieces of mica 45 forming the sheets 15 will hold in place to permit the winding because the films of water between the sheets will dry out only very slowly.

In making up the device the resistance element is placed between two of the sheets 11 and the entire device is subjected to pressure which will hold all of the parts permanently in position.

The device should be employed between 50 two clamping plates. In Figs. 1 and 2 I have shown a facing plate 18 and a pressure plate 19, the two being permanently secured together by beading over a marginal flange on the plate 18 into engagement with the surface of the plate 19, and also by means of rivets 20 extending through rivet holes in both plates and through the holes 13 in the insulating sheets 11. With the parts thus effectively and permanently clamped together so that the small pieces of mica cannot

shift position, the entire device is subjected to gentle heat for such period as will effectively drive out all of the water forming the films between the superposed splittings. The insulators will then be composed solely of mica splittings, and these will be as effectively held in place as though they had been cemented.

If the heating element is to be manufactured and sold as a separate article of manufacture it should be permanently clamped in place between such plates as the plates 18 and 19. These plates serve not only to retain the mica sheets in assembled relationship but also serve to hold the splittings in distributed relationship and to protect these sheets during use. If the heating element is to be installed directly in the place of use at the time it is manufactured, the plates 18 and 19 may be entirely omitted and the clamping action effected by two parts of the device itself, for instance the facing plate and pressure plate of the flat iron. Therefore by the term "clamping plates" I mean to include either two plates provided especially for the purpose, or two plates which may form a part of the article in which the heating element is used and there perform the clamping function.

In carrying out my invention it will be noted that all of the trim from the sheets 11 and 15 will be made up merely of mica splittings and water and that upon driving out this water such splittings may be used in making up additional insulating sheets. Thus there is no waste of mica. There is likewise no cost for shellac or other cement, and the only material employed is the very inexpensive splittings. The water is merely a transitory element in that it holds the splittings together during the time they are assembled to make up the sheet and during the cutting of the sheet and the placing of the latter in final position in respect to the electric conductor.

The device is as efficient as any mica insulation can be and is far cheaper to manufacture.

Although water is the preferred liquid for use in forming the thin films which temporarily hold the splittings together, it will, of course, be obvious that any other volatile liquid may be employed, and it will also be obvious that this may be a very weak solution of an adhesive which will have the same effect in preventing shifting of the smallest pieces in the final article if the clamping effect is not uniform or is insufficient. The amount of adhesive used in the water should not be such as will prevent the reuse of the trim by redistributing in another sheet the splittings of which the trim is composed.

Having thus described my invention, what I claim as new and desire to secure by Letters Patent is:

1. The process of making an electrical insulation sheet, which includes superposing mica splittings of varying sizes, each materially smaller than said sheet and wetted with a volatile liquid, distributing said splittings to make the sheet of substantially uniform thickness, rigidly and permanently clamping said wetted splittings between opposed plates under pressure distributed throughout substantially the entire area of the opposite surfaces of the sheet to clamp said splittings together and prevent shifting thereof, and removing the liquid by evaporation whereby said splittings are permanently held in distributed relationship solely by said clamping plates.

2. An electrical insulator sheet, comprising a plurality of pieces of mica splittings of various sizes, each very much smaller than said sheet and distributed to make the sheet of substantially uniform thickness, plates extending over substantially the entire area of opposite surfaces of said sheet, and means for permanently holding said plates together to

clamp the mica splittings in distributed relationship and solely by pressure and prevent lateral shifting of the splittings during use.

3. The process of making an electrical insulation sheet, which includes superposing mica splittings of varying sizes, each materially smaller than said sheet and wetted with a volatile liquid, distributing said splittings to make the sheet of substantially uniform thickness, cutting the sheet to the desired size and shape, rigidly clamping the trimmed sheet of wetted splittings under pressure between opposed plates and in such a manner as to permit the use of said sheet in conjunction with said plates and to firmly hold said splittings together, to prevent shifting thereof, and to protect said sheet during use, and removing the liquid by evaporation while retaining the clamping plates, whereby said splittings are firmly held in distributed relationship solely by said clamping plates.
